DESIGN FOR AN ARBOR PRESS

Siegmund Mandl, Milwaukee, Wis., assignor to Blackhawk Mfg. Co., Milwaukee, Wis., a corporation of Wisconsin

Application June 14, 1939, Serial No. 85,487

Term of patent 7 years

To all whom it may concern:

Be it known that I, Siegmund Mandl, a citizen of the United States, residing in Milwaukee County and State of Wisconsin, have invented a new, original, and ornamental Design for an Arbor Press, of which the following is a specification, reference being had to the accompanying drawing, forming part thereof.

In the drawing:

Fig. 1 is a perspective view showing one side of an arbor press, embodying my new design; and

Fig. 2 is a top view of the same tool.

I claim:

The ornamental design for an arbor press, as shown.

SIEGMUND MANDL.
